COMBINED SIGNAL CONTROL PANEL AND BOX

Arthur W. Fruh, 1874 Fremont St., Chicago, Ill.

Filed Mar. 29, 1957, Ser. No. 45,503

Term of patent 14 years

(Cl. D26—13)

Fig. 2.

FIG. 1 is a front perspective view of a combined signal control panel and box showing my new design, the same being equipped for twelve circuits, and

FIG. 2 is a perspective view of the combined signal control panel and box of my design as equipped for six circuits.

The bottom of the box is like the top while the opposite side and back are conventional in appearance.

I claim:

The ornamental design for a combined signal control panel and box, as shown and described.
